RIBBON SPREADING DEVICE FOR CARBON
COPY MAKING ATTACHMENTS FOR TYPE-
WRITERS

Josefine Rosa Geser, Zurich, Switzerland

Application September 13, 1941, Serial No. 410,784
In Switzerland November 12, 1940

5 Claims. (Cl. 197—153)

The present invention relates to typewriter attachments for making carbon copies without the use of carbon paper. More particularly it relates to mechanism for spreading the ribbons apart to facilitate the insertion of paper sheets when a plurality of manifolding ribbons are used, as in an arrangement for making a plurality of carbon copies simultaneously.

The object of the invention is to provide means for permitting the ribbons to be spread apart when the attachment is swung away from the platen, and to be restored to writing position when the attachment is returned to writing position. It embraces a lever carried by each of the ribbon spool housings at the end of the platen, said lever being connected to a spreader cam or eccentric which operates to spread the ribbons apart when the attachment is swung away from writing position. It also includes as a part of the lever an arm which is effective to restore the parts to writing position when the attachment is swung back toward the platen after the insertion of sheets. This latter action is facilitated by making the front or foremost ribbon guide members of resilient sheet metal which serves to restore the parts under its action. An operating handle is provided on each of the levers at the front of the device and conveniently accessible to the operator.

An embodiment of the invention is illustrated in the accompanying drawing by way of example, wherein:

Fig. 1 is a plan view of an attachment embodying the invention and applied to a typewriter.

Fig. 2 is a side view of the attachment viewed in the direction of the arrow A of Fig. 1 with the attachment shown in writing position.

Fig. 3 is a front view of a portion of the device showing the front ribbon guide member with the operating handle of the spreader being cut away along the line II—II of Fig. 2.

Fig. 4 is a side view of the apparatus viewed in the direction of the arrow A of Fig. 1 showing the attachment swung out of the writing position.

Fig. 5 is a front view of a portion of the attachment with the front guide member partly cut away to expose the rear guide member.

In the following description, only the parts of the device located at one side of the attachment will be described inasmuch as the others may be regarded as mirror images thereof viewed from a central plane.

In the drawing, 1 designates the platen of a typewriter, to which the attachment is applied.

Knobs 1a and 1b are provided at the ends of the platen. 2a and 2b designate ribbons (e. g. two of them) used on the device, these ribbons being superposed and being wound upon the common spools 3a and 3b. 8 designates two paper guide rollers which are adapted to be axially displaced on a rod 10 in the usual manner. The rod 10 is carried at its ends by swinging arms carried by the casing 6. The front guide member of the casing is indicated by 6a. The driving element of the ribbon spool 3a consists of the gear 5 which is driven by an intermediate gearing through agency of a toothed friction roller or gear 15. The inner or rear ribbon 2a runs over the tension roller 23 and around the stud 4 to the guide member 28, and the front ribbon 2b is led by the carrier 26 to the guide member 29.

A lever is pivotally journaled on the stud 4 carried by one wall of housing 6, this lever being provided with a spreader cam or eccentric 7, a handle 9, and an arm 12. The front guide member 29 about which the ribbon 2b is conducted is resiliently constituted and is fastened by screws 13 to the rear guide member 28 about which the ribbon 2a is conducted. The front guide member 29 presses, due to its own resiliency, against the spreader cam 7. The parts are so arranged that when the front guide member 29 is lifted, the arm 12 is in such a position that when the attachment is swung back into writing position, the arm strikes against the platen 1, (see Fig. 4). Further swinging of the attachment in the direction of the arrow B serves to swing the arm 12 upward in the direction of arrow C until it finally reaches the position shown in Fig. 2. The spring pressure exerted by the front guide member on the spreader cam 7 assists this action until the guide members, and hence the ribbons are in the writing position of Fig. 2.

A centering stud 14 attached to the guide member 28 and passing through the guide member 29 guides the latter in its movements. A funnel-like member 16 fastened to the guide member 28 serves to guide the ribbons 2a and 2b.

The operation of the attachment is as follows:

When the attachment is swung away from the writing position of Fig. 2 and into the position of Fig. 4, turning the handle 9 in the direction of arrow D serves to spread the ribbons apart by the amount indicated a. With the parts in this position, the writing sheets are inserted between the ribbons. The attachment is then swung in the direction of arrow B again into the writing position. As the attachment is swung in direc-

tion B, the arm 12 strikes against the platen 1; the spreader cam 7 is turned down and the guide member 29 following the action of the spreader cam is pressed against the guide member 28. Writing on the inserted sheets can now be started.

The arm 12 has been indicated as striking the platen 1 when the attachment is swung back into writing position. It could obviously be caused to strike against any abutment on the typewriting machine instead of against the platen, and for the same purpose, without departing from the spirit and scope of the invention.

It will be clear that the above device provides a simple and effective method of spreading the ribbons apart for the insertion of paper sheets and without unduly complicating the mechanism. It will be understood that in practice, the ribbons 2a and 2b, driven from the platen by gearing 15, 5, will progress past the platen as a sheet is being typed, also that when the ribbons have traveled across in one direction, they will be reversed for their return traverse. Devices of this type are known, for example that disclosed in my copending application Serial No. 289,079, filed August 8, 1939, may be used. Obviously the use of the invention is not limited to that particular structure.

Having thus described my invention, what is claimed is:

1. In an attachment for typewriters, a frame adapted for mounting on a typewriter carriage and having a ribbon spool adjacent each end thereof; a housing for each of said spools; a pair of ribbons wound in superposed relation on said spools and connecting them; means for pivotally mounting said frame to bring it into writing position with said ribbons adjacent the writing field of the typewriter platen or to retract it and swing said ribbons away from said platen; a pair of superposed ribbon guide members on each of said housings; and means comprising an eccentric pivoted on each of said housings and an actuating handle therefor for spreading said ribbon guide members and the ribbons carried thereby apart when the frame is swung away from writing position.

2. In an attachment for typewriters, a frame adapted for mounting on a typewriter carriage and having a ribbon spool adjacent each end thereof; a housing for each of said spools; a pair of ribbons wound in superposed relation on said spools and connecting them; means for pivotally mounting said frame to bring it into writing position with said ribbons adjacent the writing field of the typewriter platen or to retract it and swing said ribbons away from said platen; a pair of superposed ribbon guide members on each of said housings; eccentric means carried by each of said housings and an actuating handle therefor for moving and holding said ribbon guide members and said ribbons in spaced relation when the frame is moved away from writing position; and means actuated by restoration of said frame to writing position for again actuating said eccentric to restore the ribbons to writing position.

3. In an attachment for typewriters, a frame

adapted for pivotal mounting on a typewriter carriage, said frame having a writing position and a retracted position; a ribbon spool housing adjacent each end of the frame; a ribbon spool rotatably mounted in each of said housings and carrying a pair of superposed ribbons; platen actuated means for unwinding said ribbons from one of said spools and winding them on the other; a pair of superposed ribbon guide members on each of said housings, the outer of said members being resilient; a lever pivoted on each of said housings and having an extension for engaging said platen when the frame is retracted; and an eccentric pivoted to each of said levers and having an actuating handle for bringing and holding said ribbons in spaced relation when the frame is positioned away from writing position, said extension being effective when the frame is restored to writing position to actuate said eccentric and to permit restoration of the ribbons to writing position under the action of said resilient guide members.

4. In an attachment for typewriters, a frame adapted for pivotal mounting on a typewriter carriage, said frame having a writing position and a retracted position; a ribbon spool housing adjacent each end of the frame; a ribbon spool rotatably mounted in each of said housings and carrying a pair of superposed ribbons; platen actuated means for unwinding said ribbons from one of said spools and winding them on the other; a pair of superposed ribbon guide members on each of said housings, the outer of said members being resilient; a pivoted lever on each housing and extending through both of the guide members, said lever having an operating handle at the front of the machine, and a platen engaging extension projecting rearwardly; and eccentric means fixed to said levers and actuated by movement of said levers for spreading the associated guide members and the ribbons apart when the frame is in retracted position, and restoring the ribbons to writing position through resiliency of the guide members when the frame is restored to writing position.

5. In an attachment for typewriters, a frame adapted for pivotal mounting on a typewriter carriage, said frame having a writing position and a retracted position; a ribbon spool housing adjacent each end of the frame; a ribbon spool rotatably mounted in each of said housings and carrying a pair of superposed ribbons; platen actuated means for unwinding said ribbons from one of said spools and winding them on the other; a pair of superposed ribbon guide members on each of said housings, the outer of said members being resilient; a lever pivoted on each of said housings and having an extension for engaging said platen when the frame is retracted; and eccentric means rendered effective when the frame is in retracted position for permitting actuation of said levers to space said ribbons apart, and to permit restoration by said resilient members of the ribbons to writing position when the frame is restored to writing position.

JOSEFINE ROSA GESER.
